STORAGE JACK BOX FOR HEAD SETS

Thomas Albert Scanlon, Barrington, R.I., assignor to
Avid Corporation, East Providence, R.I., a corpora-
tion of Rhode Island

Filed Jan. 19, 1970, Ser. No. 20,973

Term of patent 14 years

Int. Cl. D14—03

U.S. Cl. D26—14

FIG. 1 is a perspective view of a storage jack box for head sets showing my new design;

FIG. 2 is a front elevational view thereof;

FIG. 3 is a left hand elevational view of FIG. 1; and
FIG. 4 is a vertical cross sectional view taken on line
4—4 of FIG. 2.

I claim:

The ornamental design for a storage jack box for head sets, as shown.
